AIR PURIFYING AND CIRCULATING DEVICE

George S. Dauphinee, Brooklyn, N. Y., assignor to
 W. B. Connor Engineering Corp., New York,
 N. Y., a corporation of New York

Application July 23, 1949, Serial No. 106,472

7 Claims. (Cl. 183—4.8)

1

This invention relates to air purifying and circulating devices and is concerned more especially with such devices particularly adapted for use in connection with large refrigerator cabinets or walk-in boxes, such as are employed in hotels, restaurants, butcher shops, hospitals and the like.

Since a large variety of types of foods is customarily stored in refrigerated cabinets of the character indicated, objectionable cross-transference of odors and flavors will normally occur unless particular care is exerted to provide air-tight packaging and segregation of the potentially offensive food articles. Such segregation and packaging is troublesome, time-consuming and expensive. Furthermore, recent research indicates that when the air within such refrigerated cabinets is maintained at a low concentration with respect to deleterious adulterant gases, the storage life of the food products is greatly prolonged and odor or flavor transference is not perceptible even without segregation of the food products or special packaging.

Accordingly, it is a primary object of the invention to provide a device for effectively adsorbing odors and circulating air in a refrigerated enclosure of the type indicated.

Another object of the invention is the provision of an air purifying and circulating device which is designed and constructed in such a manner as not to require an enclosing housing or cabinet and which may be fabricated as an extremely simple and compact unit at low cost.

An additional object of the invention is the provision of a device of the character indicated which provides not only for air circulation through an adsorbent medium, such as activated carbon, but which includes novel means for adjusting the air discharge direction.

A further object of the invention is the provision of a device of the character indicated having improved means for varying the quantity or volume of air circulated therethrough and which is further characterized by a simple means of installation within the storage space or cabinet.

The foregoing objects as well as additional objects and advantages of the invention will be readily understood in the course of the following detailed description taken in connection with the accompanying drawings, which illustrate a preferred embodiment of the invention, and wherein:

Fig. 1 is an elevational view, partly in section, of an air purifying and circulating device embodying the features of the invention;

Fig. 2 is a top plan view partly broken away to illustrate the manner of mounting the carbon canisters on the device;

2

Fig. 3 is an end elevation of the device taken on the discharge or blower side, or on the left of Fig. 2; and

Fig. 4 is an end elevation of the intake side of the device with one of the canisters removed, as seen on the right of Fig. 2.

Referring now to the drawings in greater detail, the device includes a blower assembly generally designated by reference numeral 10 which is adjustable for varying the direction of air discharge, as will be more fully described hereinbelow. Blower assembly 10 is operatively associated with an air purification unit 11 which may conveniently take the form of double-walled perforate canisters 12 containing suitable adsorbent material, such as granular activated carbon 13.

A motor 14 is mounted in any suitable manner on blower housing 15 for powering the blower fan 16 in order to discharge purified air through the blower outlet duct 17. An important feature of the invention resides in mounting blower housing 15 on base plate 18 in such a manner as to vary the direction of air discharge therefrom. For this purpose blower housing 15 is provided with a dished ring 19 secured thereto in any preferred manner as by means of welding. Ring 19 thus provides a circular track or channel for base plate 18 which is provided with a suitably dimensioned central aperture defining an air inlet 20 to the blower housing 15. By reason of the described arrangement blower assembly 10 may be rotated to discharge air in any desired direction, as clearly shown in Fig. 3 in broken outline, and the blower housing 15 will be retained in any adjusted position by means of frictional engagement between dished ring 19 and base plate 18 or, if desired, additional retaining means may be employed. The marginal edges of base plate 18 are bent inwardly as shown at 21 to provide the desired stiffness and rigidity for said plate.

The air purification unit 11 including the carbon canisters 12 is secured to base plate 18 by means of a manifold box or pan 22 which may be secured to said base plate by means of connecting bolts 23. Manifold box 22 is provided with mounting apertures 24 for the reception of the ends of carbon canisters 12 thus the base plate 18 together with the manifold box 22 form a plenum chamber wherein the air drawn through the canisters 12 is received preliminary to being drawn through the device. In order to securely retain the canisters 12, a suspension element or bar 25 is secured inside manifold box 22 preferably extending diametrically with respect to

the air inlet 20, as shown clearly in Fig. 4, said suspension element being mounted in any desired manner as by means of tabs 26. As best shown in Fig. 1, suspension element 25 is recessed at 25a in the region of the mounting apertures 24 of manifold box 22 in order to allow reception of the inner end caps 12a of carbon canisters 12 therewithin. Retainer rods 27 preferably in the form of hookbolts are engaged in suitable mounting holes 28 of suspension bar 25 and extend substantially axially of the canisters 12 to project slightly outwardly of the outer end caps 12b. A cover plate 29 is mounted on retainer rod 27 abutting outer end cap 12b of canister 12 and wing-nut 30 is clamped against cover plate 29 on the threaded outer end of each retainer rod. Cover plate 29 is preferably provided with an inwardly turned flange 29a which extends over the projecting rim of canister end cap 12b in order to prevent distortion when clamping pressure is applied by wing-nut 30. As shown in Fig. 2, the hooked end 27a of each retainer rod is formed in such a manner as to prevent easy removal of said rod when it is desired to remove and renew the canisters 12.

Thus when blower fan 16 is in operation, odor-laden air is drawn from the atmosphere surrounding the canisters 12, first passing through the perforated outer wall 31, then through the activated carbon 13 or other adsorbent material and then through the inner wall 32 of each of said canisters, whereupon the objectionable odoriferous adulterants are removed and the purified air passes into the manifold box 22. The purified air then passes into the blower housing 15 through the air inlet opening 20 defined in base plate 18 to be finally discharged from the device in a directed stream through blower outlet duct 17 under the influence of blower fan 16.

In addition to the described means for adjusting the air discharge direction, the device is provided with damper means for varying the volume of air circulated therethrough so that a single standard size unit may serve effectively for a large number of differently sized refrigerated cabinets. For this purpose a damper plate 33 is pivotally mounted on the inside of base plate 18 at 34 for throttling the air inlet 20 to blower housing 15. The damper travel is controlled by means of an externally accessible screw 35 fixed to damper plate 33 and extending through an arcuate guide slot 36 in base plate 18. A clamping nut 37 operated to lock the damper plate 33 in any desired adjusted position. By adjusting the damper plate to positions intermediate the open position of Fig. 3 (in dotted outline) and the maximum throttled position of Fig. 4 (in dot-dash outline) the device may be readily adjusted to the desired discharge volume of purified air.

The device may be easily mounted at any convenient space on the wall or ceiling of the refrigerated cabinet by means of slotted hanger lugs 38 which may be spot welded to the top and bottom of manifold box 22. Thus only two screws or other fastening elements are required and by backing off the screws a couple of turns, the device may be easily removed for inspection, adjustment or removal of the canisters 12.

The design and construction of the present invention makes possible a device characterized by extreme simplicity, compactness and adaptability to varying requirements. The employment of an enclosing jacket or cabinet is eliminated

and the incorporation of novel adjustable features for varying the direction of air discharge and volume of air circulated through the device makes it possible to fabricate a low-cost unit which will serve effectively for refrigerated cabinets of varying size. The efficiency of the device is attested to empirically by the fact that a satisfactory degree of purity was maintained when air was circulated through cocoanut shell activated carbon at a rate of one air turnover in ten to fifteen minutes.

Since certain modifications may be made in the device of the present invention without departing from the scope thereof, it is intended that all matter contained in the foregoing description and shown in the accompanying drawings, be interpreted merely as illustrative and not in a limiting sense.

What is claimed is:

1. In an air purifying and circulating device, a base element having an attached manifold member, a blower housing rotatably mounted on one side of said base element for varying the direction of air discharge therefrom, removable air-permeable odor adsorbent members mounted on the opposite side of said base element against the manifold member, said members comprising double-walled perforate canisters, a suspension element secured to said manifold member for retaining said adsorbent members, hookbolts carried by said suspension element and adapted to support said canisters in substantially axial position, each of said canisters having a cover plate insertable over the free outer end of a respective hookbolt, and a clamping member engageable on each of said hookbolts and against a respective cover plate, said base element defining an inlet opening into said blower housing for conveying purified air thereinto from said odor-adsorbent members, said base element having adjustably pivoted damper means for controlling the air flow from the blower housing and after the air has passed through the canisters.

2. In an air purifying and circulating device, a base element, a blower housing rotatably mounted with respect to said base element, said base element having an aperture defining an inlet opening into said housing, said housing having a dished ring frictionally engaged about the aperture of said base element, a manifold element secured to said base element, a plurality of air-permeable, odor-adsorbent members removably associated with said manifold element, said members comprising double-walled perforate canisters, a suspension element secured to said manifold element for retaining said adsorbent members, hookbolts carried by said suspension element and adapted to support said canisters in substantially axial position, each of said canisters having a cover plate insertable over the free outer end of a respective hookbolt, and a clamping member engageable on each of said hookbolts and against a respective cover plate.

3. In an air purifying and circulating device, a base element, a blower housing rotatably mounted with respect to said base element, said base element having an aperture defining an inlet opening into said housing, said housing having a dished ring frictionally engaged about the aperture of said base element, a manifold element secured to said base element, a plurality of air-permeable, odor-adsorbent members removably associated with said manifold element, said members comprising double-walled perforate canisters, a suspension element secured

to said manifold element for retaining said adsorbent members, hookbolts carried by said suspension element and adapted to support said canisters in substantially axial position, each of said canisters having a cover plate insertable over the free outer end of a respective hookbolt, and a clamping member engageable on each of said hookbolts and against a respective cover plate, said base element having adjustably pivoted damper means accessible externally thereof for throttling the inlet opening into said blower housing.

4. In an air purifying and circulating device, a base element forming a plenum chamber, a blower housing rotatably mounted on one side of said base element for varying the direction of air discharge therefrom, said blower housing having an air-discharge outlet, air-permeable odor-adsorbent means mounted on the opposite side of said base element, said base element defining an inlet opening into said blower housing for conveying purified air into said plenum chamber from said odor-adsorbent means, and a power-driven fan mounted inside said blower housing for drawing odor-laden air through said odor-adsorbent means and through said plenum chamber and discharging purified air from the outlet of said housing, and throttling means located between the odor-adsorbent means and the air-discharge outlet for regulating the amount of air drawn through said odor-adsorbent means.

5. In an air purifying and circulating device, a base element forming a plenum chamber, a blower housing rotatably mounted on one side of said base element for varying the direction of air discharge therefrom, said blower housing having an air-discharge outlet, air-permeable odor-adsorbent members mounted on the opposite side of said base element, said members comprising double-walled perforate canisters closed at their outer ends, said base element defining an inlet opening into said blower housing for conveying purified air into said plenum chamber from said odor-adsorbent members, a power-driven fan mounted inside said blower housing for drawing odor-laden air through said odor-adsorbent members and through said plenum chamber and discharging purified air from said housing, and throttling means located between the odor-adsorbent members and the air-discharge outlet for regulating the amount of air drawn through said odor-adsorbent means.

6. In an air purifying and circulating device a base element, a manifold element secured thereto, a blower housing rotatively mounted with respect to the base element, said base element having an aperture defining an inlet opening into said housing, said housing having a dished ring extending over and frictionally engaging the marginal edge of the base element around said aperture to thereby securely but ad-

justably attach the housing to said base member, the manifold element consisting of a box-like enclosure having one wall formed by the base member and having a second wall spaced from said base member and provided with canister-receiving openings, odor-adsorbent members in the form of double-walled perforate canisters mounted on the second wall of the manifold member and seated in the openings therein, a suspension element extending across the manifold element between the walls thereof for retaining said canisters, means for attaching the canisters to the manifold member and supporting said canisters in substantially axial position, each of the canisters having a cover plate on its free outer end held in position by a hook-bolt.

7. In an air purifying and circulating device, a base element forming a plenum chamber, a blower housing mounted on one side of said base element for varying the direction of air discharge therefrom, a plurality of air-permeable odor-adsorbent elements mounted on the opposite side of said base element, each of said odor-adsorbent elements consisting of a double-walled cylinder having an outer foraminous wall and a spaced inner foraminous wall with odor-adsorbent material arranged in the spacing between the said inner and outer walls, said space between the walls being closed at each end of the cylinder, the cylinders being arranged in spaced relation and being exposed to room air, the base element having apertures in one of its walls against which one end of each cylinder is arranged to thereby establish communication between the interior of each of the cylinders and the plenum chamber, said base element defining an inlet opening into said blower housing for conveying purified air which has passed through the walls of the cylinders into said plenum chamber, a power-driven fan mounted inside of the blower housing for drawing odor-laden air through said odor-adsorbent means and through the plenum chamber and discharging purified air from the housing, and means at the outer ends of the cylinders for closing said ends of the cylinders.

GEORGE S. DAUPHINEE.
